UNITED STATES PATENT OFFICE.

GEORGE A. WELD, OF WINCHESTER, MASSACHUSETTS.

SHOE-CLASP.

SPECIFICATION forming part of Letters Patent No. 404,023, dated May 28, 1889.

Application filed November 19, 1888. Serial No. 291,272. (No model.)

To all whom it may concern:

Be it known that I, GEORGE A. WELD, of 5 Winchester, in the county of Middlesex and State of Massachusetts, have invented a new and useful Improvement in Shoe-Clasps, of which the following, taken in connection with the accompanying drawings, is a specification.

The object of my invention is to so construct 10 a device that the parts when united may together form a cheap, easily-working, and durable clasp. This object I attain by the construction shown in the accompanying drawings, in which—

15 Figure 1 is a plan of one of my clasps complete. Fig. 2 is a longitudinal section taken on line $x-x$ of Fig. 1. Fig. 3 is a section, in part, taken on line $y-y$ of Fig. 1. Fig. 4 is a plan of the part that forms the spring-plate; 20 also shows a part of the tongue. Fig. 5 is a cross-section taken on line $z-z$ of Fig. 1. Fig. 6 is a cross-section taken on line $z-z$ of Fig. 8. Fig. 7 is a plan of the base-plate of the clasp as it is made by the blanking-die, and Fig. 8 25 is the base-plate of the clasp as it appears when the pivot-holders are folded back onto the plate.

The attaching-plate B, Figs. 1 and 2, is made with openings $C C' C^2 C^3$, in the usual 30 manner, and adapted to engage with the tongue D.

The main plate A is first cut into the form shown in Fig. 7, it having ears $H H H H$, as shown. These ears are bent back and folded 35 onto the plate, as shown in Figs. 3, 5, 6, and 8, so as to form stay-pieces for the pivots d (see Figs. 3, 4, and 5) for the tongue D.

The plate A is folded on the line n , Fig. 7, so as to inclose the pivots d of the tongue 40 D, and also embrace the spring-plate E, Fig. 2. It is then made fast by the rivet A^2 , which passes through holes $a a'$ of the plate A and a^2 of the spring-plate E. Thus the single rivet a^2 holds the whole firmly together.

45 As the end D' of the tongue D extends beyond the pivots d , (see Fig. 4,) it is evident

that the act of turning this up to connect or detach the plate B will cause a deflection of the spring-plate E, and that the reaction of the spring-plate E will have a tendency to 50 hold the tongue D in either position, open or shut.

The main plate A has depressions $A^3 A^3$, (see Figs. 8 and 2,) to make room for the ears $H H$ and pivots $d d$. (See Fig. 3.)

55 By the device of the folded-back ears $H H$ and the depression A^3 , I am enabled to secure a firm and compact socket for the pivots $d d$ of the tongue D to rest in.

In order to cause the cross-bars $K K K$ of 60 the attaching-plate B to stand somewhat above the level of the under side of the plate B, and thus engage in a better relative position with the tongue D, I form ribs $B' B'$ on the under side. (See Figs. 1 and 2.) These ribs $B' B'$ 65 also render the bearing-surface of the plate B on the vamp much better adapted to fit easily, and not to chafe or wear the vamp.

I am aware that it is not new to bend the ears at right angles on clasp-plates for the 70 purpose of forming guards to hold the hinge-pins. My device consists in folding the ears $H H$ back onto the plate and in holding them firmly between the folds of the plate, as shown in Fig. 3.

75 I claim—

1. In a shoe-clasp, the combination of the main plate A, having inwardly-folded ears $H H$ and depressions $A^3 A^3$, adapted to be doubled onto itself, with the tongue D, substantially as described, and for the purpose set forth.

2. In a shoe-clasp, the attachment-plate B, having depressed ribs $B' B'$, adapted to rest upon the sides of the clasp-plate A A' and to 85 hold the cross-bars $K K K$ above the spring-plate E, with the spring-plate E and clasp-plate A A', substantially as described.

GEORGE A. WELD.
